CLAIM

The ornamental design for a roll dispenser handle, as shown and described.

DESCRIPTION

FIG. 1 is an isometric view of a roll dispenser incorporating our new roll dispenser handle design, viewed from above, in front of, and from the left side of the roll dispenser handle; FIG. 2 is an alternative isometric view, viewed from above, in front of, and from the left side of the roll dispenser handle; FIG. 3 is a front elevation view thereof; FIG. 4 is rear elevation view thereof; FIG. 5 is a left side elevation view thereof; and, FIG. 6 is a top plan view thereof.

The broken line showing of parts of the drawings is included for the purpose of illustrating portions of the “article” and environment and forms no part of the claimed design.

1 Claim, 6 Drawing Sheets(56)
